CLAIM

The ornamental design for a mobile device holder with pocket, as shown and described.

DESCRIPTION

FIG. 1 is a front elevation view of a mobile device holder with pocket showing my new design;

FIG. 2 is a left side elevation view thereof;

FIG. 3 is a right side elevation view thereof;

FIG. 4 is a top view thereof;

FIG. 5 is a bottom view thereof;

FIG. 6 is a rear elevation view thereof;

FIG. 7 is a cross-section taken along line 7-7 in FIG. 3;

FIG. 8 is a front elevation view of a second embodiment of a mobile device holder with pocket showing my new design;

FIG. 9 is a left side elevation view thereof;

FIG. 10 is a right side elevation view thereof;

FIG. 11 is a top view thereof;

FIG. 12 is a bottom view thereof; and,

FIG. 13 is a rear elevation view thereof.

The broken lines in the drawings depict parts of the mobile device holder with pocket that form no part of the claimed design.
